AUTOMATIC MOISTURE CONTENT DETERMINATION AND CONTROL APPARATUS

Shinichi Sasaki, 144 5-chome, Tokiwa-cho, Urawa City, Saitama-ken, Japan

Filed Oct. 12, 1959, Ser. No. 846,018

3 Claims. (Cl. 324—58.5)

The present invention relates to an apparatus for determination and control of moisture content in such hygroscopic webs as of fibre, cloth, pulp and other items, especially in samples of goods of such materials during the course of manufacture by utilizing the attenuation phenomenon of the microwave for moisture content.

There has been generally proposed, for electric determination of moisture content in webs of fibre, cloth, paper, pulp and others, a number of such methods as would stand on the basis of resistance, dielectric constant or dielectric loss, and has been adopted for experimental purpose in determining the moisture content in standing material. Determination of the moisture content in material during the course of manufacture is essentially liable to considerable errors which are ascribable to such major sources as (1) variations of position of the sample relative to the electrodes, (2) changes of dielectric constant of air with relative humidity, (3) variations of the temperature of electrodes, (4) mechanical instability of the position of the electrodes to each other. Any existing method for determination of moisture content on the basis of measurements of resistance or dielectric constant, because of influences from such undesirable factors as stated above does not as yet cease to show remarkable errors which could hardly be reduced to the minimum.

Now, making a point of a microwave phenomenon in which the microwave undergoes sensible attenuation for moisture content in sample, the idea has been to determine the moisture content by turning the attenuation factor of the microwave into moisture contents. According to the present invention, the determination of moisture content in sample on measurements of the microwave attenuation factor has proved as practical as theoretically to be accurate, in case of paper web by simple compensation with the basis weight and temperature measurements as accurately as any existing method. In addition, corrections on compensated measurements are comparatively not only easily made but also errors resulting from such sources as shown above may be reduced to the possible least degree, and the application of an automatic balancing system for microwave attenuation renders laudable sensitivity and stability of operation all thru the time.

One of the objects of the present invention is to provide means that the moisture content in sample should be determined on the knowledge of measurements of the attenuation factor of the microwaves in the waveguide by making a slot, in the direction in which the microwaves proceed or with a certain proper angle, prepared in a part of the waveguide for the moving sample to pass through.

Another one of the objects of the present invention is to provide means that the moisture content determined on the knowledge of attenuation factor of the microwaves in the wave guide should be recorded and that the control of the steam valve, that uses full control over moisture content in sample, should be made by a controller which works in co-ordination with the attenuation factor of the microwaves in the waveguide to the perfect automatic insurement of a certain prescribed standard of moisture content in such goods as fibre, cloth, paper, pulp and the like webs.

Another one of the objects of the present invention

2

is to provide means that not only the moisture content in sample should be brought to knowledge on the basis of microwave attenuation factor in the waveguide as shown above, but also a microwave automatic balance method should be introduced that should work thru any unit operation time with high sensitivity and stability. The system generally includes an oscillator and a pair of magic T circuits coupled by two waveguides, a transfer shutter is provided to allow the microwaves to proceed, periodically and alternately, into two waveguides, namely a comparison waveguide and a measurement waveguide, the latter for passage of sample.

Another one of the objects of the present invention is to provide means so that the determination of moisture content in sample should be recorded in a potentiometer type recorder.

Other objects of the present invention, together with their many advantages they bring, will be clarified in the following description and the accompanying drawing, in which:

FIGURE 1 is a combination block and schematic diagram of the device contemplated herein; and,

FIG. 2 is a graphic explanation of the wave forms produced by the device of FIG. 1.

Referring to the drawing for specific details of the present invention, electric power supply ES feeds source 1 for oscillator 2, such as klystron and the like, potentiometer type recorder 19, air system automatic controller 20, amplifier 21, synchronizing signal amplifier 22 and driving motor 23. Two magic T circuits on both sides 24 and 25 contain comparison waveguide 27 with comparison attenuator 26, the weight correction attenuator 28 and the balance attenuator 29. Two attenuators 28 and 29 are coupled across measurement waveguide 4 with a slot d which extends along in the direction in which the microwaves proceed and lets moving sample 5 thru. The input circuit has the oscillator 2 and buffer attenuator 3, and at the cross of the magic T circuit 24 is placed a transfer shutter 31 which is rotated by a driving motor 23 with a permanent rotor 30 affixed on axle. The detector h, which is placed at end of the output circuit, connects its output circuit with the input one of amplifier 21 which has connection with driving coil 33 for two-phase motor 32, excitation coil 34 is connected to the output circuit of synchronizing signal amplifier 22, the input circuit being connected with the both ends of induction voltage coil 36, which, together with the permanent magnet rotor 30 affixed on the rotating axle of driving motor 23, composes generator 35. The rotation of the two-phase motor 32 may make balance attenuator 29 variable, and is connected with a variable resistance 38 in one of the arms of bridge circuit 37. The bridge circuit 37 is connected with a potentiometer type recorder 19, which is connected with an air system controller 20 for control of the steam control valve 39 prepared in the canal for steam supply for control of moisture content in sample. In the drawing 40 and 40' show non-reflection terminals, 41 an air supply and 42 a variable resistance for control of sensitivity of the bridge circuit 37. Operation of the example shown above takes place as follows: the source ES is switched on, the microwaves from the oscillator 2 proceed to be modified to be of proper strength by proper management of the buffer attenuator, then to the transfer shutter 31, are divided into two groups to proceed further into the two canals, namely, the comparison waveguide 27 and the measurement waveguide 4 alternately in about 30 c./s.—50 c./s.; therefore, the microwaves going into one arm of the magic T circuit 25 thru the comparison attenuator 26 and those into another arm of the circuit to go thru the slot d with sample and the balance attenuator 28, al-

ternately reach the detector *h*. When now such microwaves as shown above alternately proceed thru the two canals in two groups, are so managed to hold balance with themselves by regulating the comparison attenuator 27, the output wave forms of the amplifier 21 and the detection output of the detector *h* present such wave forms as shown in A and B of FIG. 2 and the two-phase motor 32 keeps standstill. But, when the moisture content in sample moving thru the slot *d* changes and correspondingly the attenuation factor of the microwaves in the measurement waveguide 4 changes, balance between those microwave groups in the two waveguides 27 and 4 is lost. The wave form of the detection output in this moment of the detector *h* and that of the output of the amplifier 21 are as shown in C and D, of FIG. 2; the synchronizing frequency portion of the wave form of the latter manifests such appearance as shown by a dotted line and consequently, phase difference is produced with the waveform of the output of the synchronizing signal amplifier 22, the synchronizing signal itself being induced in the induction voltage coil 36 by the rotation of the rotor 30 affixed on the rotary axle of the driving motor 23 which operates the transfer shutter 31. The two-phase motor 32 begins to rotate with its driving coil 33 being connected with the output circuit of the amplifier 21 and its exciting coil 34 with the output circuit of the synchronizing signal amplifier 22, and the interlocking balance attenuator 29 works and the two-phase motor 32 will not come to standstill until the two groups of microwaves from the two waveguides 29 and 4 come to a balance. The two-phase motor rotates, i.e. in proportion to the change introduced in the moisture content in sample 5. The rotating axle of the two-phase motor 32 is connected with the variable resistance 38 in one of the arms of the bridge circuit 37, and the rotary angle of the rotating axle is turned into phase difference, and recording is made by the potentiometer type recorder. The control of the steam control valve by working an air system automatic controller 2 corresponding to indications by the recorder makes it feasible to make an automatic and uninterrupted production of samples of definite moisture contents by providing samples with steam supply correcting deviations from the prescribed band of moisture content in sample.

Said example has it too that the determination of the moisture content in the sample is made on the basis of the attenuation factor of the microwave affected by the moving sample thru the slot prepared in the waveguide. Application however to the use of an automatic balance circuit for microwaves as shown above, neutralizes possible output fluctuations for fluctuating source voltage or temperature of the oscillator, klystron and the like gives not only high stability in any unit operation, but also indications of remarkable accuracy, should a high performance variable resistance be used in the bridge circuit. Adoption of the synchronizing detection system which gives synchronizing signal and waveguide output to

the two-phase motor, enables the catching of any weakest change in moisture content in the sample and realizes measurement expressive of high sensitivity, accuracy and stability, almost perfectly free from such special influence as should come from furnish, pH, density, basis weight, thickness, ash-contents, and so on in the sample.

It is clear that the apparatus of the present invention is also able to measure to determine any variation in web density, of any part of a moving sample thru the waveguide, should moisture content in sample be held to stand at a certain definite value.

What is claimed:

1. A microwave device for determination of the moisture content in a sample which moves through the device, comprising in combination: a microwave oscillator fed by a power source; a first attenuator fed by said oscillator to maintain waves produced by said oscillator in a waveguide network; a first magic-T circuit coupled to said attenuator dividing the output from said attenuator into two parallel branches; a rotatable transfer shutter at the cross point of said magic-T including driving means therefor; a measuring waveguide fed by said first parallel branch at one end, having a longitudinal straight portion extending from said fed end; a recessed section in said longitudinal straight portion forming a slot in said measuring waveguide for passage of a sample therethrough; a comparison waveguide fed by said second parallel branch at one end; second and third attenuators in said measuring and comparison waveguide circuits; a magic-T circuit fed by the outputs of said measuring and comparison waveguide circuits including output means combining the outputs of said measuring and comparison waveguide circuits; a detector at the end of said output means; motor means responsive to said detector output and said rotatable transfer shutter driving means; a bridge circuit responsive to said motor means; and, indicator means responsive to said bridge circuit.
2. A device as claimed in claim 1, including recorder means responsive to said bridge circuit.
3. A device as claimed in claim 1, including steam control valve means responsive to said bridge circuit.
